BOBBIN STRIPPER

Julius E. Kimbirl, Charlotte, N. C., assignor to
 The Terrell Machine Company, Charlotte,
 N. C., a corporation of North Carolina

Application November 24, 1937, Serial No. 176,181

9 Claims. (Cl. 28—19)

The present invention has to do with devices for stripping the waste yarn from used bobbins which have been expelled from automatic looms.

It aims to provide a novel and improved bobbin stripping machine which will take the residual waste yarn off from the bobbins without any mechanical contact with the yarn-carrying portions thereof, so that there will be no chipping or abrasion of such portions from this cause which 5 could subsequently catch and fracture the delicate filaments of rayon or silk yarns when the bobbins are rewound and again put into use. In particular, the invention aims to produce a bobbin stripper having these advantages which 10 also has increased efficiency and simplicity while costing less to build and to operate.

To these ends, the invention consists in a bobbin stripper in which the bobbins travel along a path with their tips downward while subjected to 20 the action of a sheet or sheets of air projected against their yarn-engaging portions, to loosen and blow down the terminal ends of the yarn which remains wound on the bobbins. The sheet-like jet of air extends laterally of its direction of flow, so as preferably to engage a plurality of 25 pendant bobbins at one time, and hence so that each bobbin moving along the path will be continuously subjected to the blast throughout a prolonged period of its travel. To produce this type 30 of blast in preferred manner, a slot is used as the orifice or aperture through which the air is forced under pressure, and to keep the blast constant in intensity throughout substantially the entire exposure of each bobbin thereto, the slot is located alongside and parallel to the path of the 35 bobbins. With the jet of air thus made continuously-acting on each bobbin over a prolonged period of time, it is found that in spite of the fact that the bobbins may be constantly in motion 40 as they pass through the jet, a lessened intensity or density of the jet suffices to blow loose the terminal end of the waste yarn, especially when such jets are duplicated at opposite sides of the path of the bobbin, as preferred herein, than 45 where a series of spaced round nozzles or holes is used. Hence the use of compressors with their permanent and necessary adjuncts of compressed air tanks and piping, expensive in first cost and in power costs and upkeep, may be entirely dispensed with, and replaced by one or two relatively 50 cheap individually-driven rotary blowers or fans built in as a part of each machine, thereby making each bobbin stripper a self-contained unit detached from any piping system.

In the improved stripper of the invention the

bobbins may be propelled along their path through the air-jet either manually or mechanically, and a simple and effective mechanical method is shown comprising opposed belts running at equal speeds frictionally engaging the heads of 5 the bobbins to slide them along spaced tracks while hanging from the latter by their heads or the rings on such heads. Also, instead of relying wholly on the combined effect of gravity and the air-jets to unwind the residual yarn downwardly 10 off from the tips of the bobbins, as can be done with rayon, mechanical means such as a friction-surfaced roll or reel may be located below the path of the bobbins to engage the descending 15 ends of yarn, and rotated at high surface speed 20 to unwind the yarn off from the bobbins in short order.

Other aims of the invention, and the manner 25 whereby they are carried into effect, are as will be made plain hereinafter.

An illustrative embodiment of the invention is shown in the accompanying drawings, in which, 30

Fig. 1 is a plan view.

Fig. 2 is a view in vertical section on the line 25 2—2 of Fig. 1.

Fig. 3 is a fragmentary side elevation, with certain parts broken away.

The path of the bobbins through the machine is defined by a pair of tracks 1, 1, spaced equidistant from each other throughout their length, 30 and either level or inclined downwardly in the direction of travel of the bobbins. These tracks engage the heads of the bobbins, or better still the steel rings on the heads, to support the bobbins in pendent relation with their tips downward. 35 A hopper 3 is indicated, into which the bobbins are dumped in quantity at random, being thereafter inserted tip first by hand into the space between the tracks and being pushed or allowed to gravitate toward the center of the machine. 40

The heads of the bobbins 2 are grasped one after another between a pair of opposed endless belts 5, passing around idler pulleys 6 and driven pulleys 7 fixed on shafts 9, rotated oppositely at equal speeds through engagement of equal spur gears 11. One shaft 9 is driven through worm gear 13 fixed thereon and worm 15 on shaft 17 of electric motor 19. Belt-tighteners 21 operate in obvious manner. Belt-guides 23 hold the working 45 runs of belts 5 in gripping engagement with the sides or rings of the bobbin heads, being yieldingly pressed toward each other for this purpose by springs 25 on their mounting and supporting shafts 27, the guides 23 being flanged at their top 50 55

edges as indicated in Fig. 2 to prevent the belts from rising away from tracks 1.

- To define a long narrow aperture extending alongside the path of the bobbins 2, through 5 which aperture or slot a sheet-like jet of air can be propagated, side walls 29 are provided having oblique slots 31 formed therein and extending parallel to the working runs of belts 5 throughout practically the entire extent of such runs.
- 10 A convenient construction is illustrated, in which the side walls defining the slots are formed as portions of air-chambers 33, of which the horizontal top walls 35 form the top platform of the machine on which the tracks 1 and the belt guiding devices are mounted. These chambers 33 are closed at both ends by vertical walls 37 and throughout the area of their remote sides 39, except that a large central aperture 41 is formed in each of the latter sides to accommodate a high 15 speed aeroplane type of fan 43 each driven by its individual motor 45 mounted on frame-members 47, which latter also support the air-chambers by means of steps 49 affixed to 47. The bottom of each air-chamber 33 slopes obliquely upward to 20 cooperate with top wall 35 in funneling the blast of each fan 43 into the vicinity of slots 31.

The air thus forced into air-chambers 33 at high speed and low pressure by the fans 43 is discharged at substantially constant intensity 25 throughout the entire length of slots 31, in a plurality of sheets which are directed obliquely inwardly toward the path of the bobbins and downwardly toward the tips of the latter. As the bobbins are normally fed to the belts in a continuous 30 procession with the head of each bobbin in contact with that of the preceding and succeeding bobbins, a large number of bobbins are consequently in front of the slots simultaneously, and hence each bobbin in the procession is subjected 35 to the action of the several sheets of air travelling under pressure, continuously during its travel from one end of the air-chambers 35 to the other end thereof, which as noted means for substantially the entire length of the working runs of belts 5.

One pair of opposed slots 31 is so located and directed as to impinge initially on the yarn-carrying surfaces of the bobbins at a point relatively close to the head, so that if the end is broken off 40 close to the residual mass or feeler bunch these two sheet-jets will blow it loose and start it down the barrel of the bobbin. The other opposed slots 31 produce sheets of air impinging on the bobbin 45 farther down toward its tip, to cooperate with the upper sheet-jet in bringing down the end and continuing the unwinding action after the end has been started loose. To make the action of 50 these combined blasts more effective in pulling off the waste yarn after the end has been blown loose and the unwinding commenced, downward prolongations of the side walls 29 extending for the length of the slots are provided in the shape of baffles 51, 53.

The mechanical means shown herein for completing the unwinding of the waste yarn from the bobbins comprises a reel 55 of any desired or preferable construction having its longitudinal slats 57 clad with bristles 59 and fixed on shaft 61 mounted in bearings 63 on brackets 65 so that 55 its periphery is tangent to the plane of the bobbin axes as they proceed along the tracks 1. Baffle 53 is curved across such plane as shown in Fig. 2 to divert both the downward air currents and the descending ends of yarn 67 into engagement 60 with the bristles on reel 55, so that the ends will

be engaged thereby and wound up on the reel. Reel 55 is driven in any suitable or preferred manner, as by V-belt from pulley 57 on motor shaft 17 to larger pulley 59 on the reel shaft 61.

By reason of the downward direction of the sheets of air injected through oblique slots 31 into the flue defined by side walls 29 and baffles 51, 53, a downward flow of air is induced from above the bobbins, passing through the spaces left between adjacent bobbin heads in the procession, 10 and also down through the bores 69 of the bobbins, serving both to bring down the ends of the waste yarn, and also to clean lint and fluff out of the bobbin-bores.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but

What I do claim is:

1. In a bobbin stripper, in combination, means for guiding the bobbins along a path with their tips pointing downwardly, a side wall defining a long narrow aperture which extends alongside such path, and means propelling air through such aperture to impinge initially on the yarn-carrying portions of the bobbins as the latter move sidewise along such path. 25

2. In a bobbin stripper, in combination, means for guiding the bobbins along a path with their tips pointing downwardly, a side wall defining a long, narrow aperture which extends alongside such path, and means propelling air through such aperture to impinge initially on the yarn-carrying portions of the bobbins as the latter move sidewise along such path to blow loose the ends of 35 yarn, and mechanical means to engage and draw off the ends of yarn thus loosened. 40

3. In a bobbin stripper, in combination, means for guiding the bobbins along a path with their tips pointing downward, side walls extending along said path and spaced therefrom defining a slot, and means propelling air through such slot, the side walls directing the air obliquely against the bobbins to impinge on the yarn-carrying portions of the bobbins as the latter move along such path. 50

4. In a bobbin stripper, in combination, means for guiding the bobbins along a path with their tips pointing downward, side walls extending along said path and spaced therefrom defining a slot, and means propelling air through such slot, the side walls directing the air downwardly to induce a flow of additional air from above the bobbins moving axially of the bobbins from head to tip thereof as the bobbins move along such path. 55

5. In a bobbin stripper, in combination, means for guiding the bobbins along a path with their tips pointing downward, side walls extending along said path and spaced therefrom defining a slot, and means propelling air through such slot, the side walls directing the air downwardly to induce a flow of additional air from above the bobbins moving axially of the bobbins from head to tip thereof as the bobbins move along such path to blow loose the ends of yarn, and mechanical means to engage and draw off the ends of 65 yarn thus loosened. 70

6. In a bobbin stripper, in combination, means for guiding the bobbins along a path with their 75

tips pointing downward, a source of air under pressure, and means directing such air obliquely downward against the bobbins in a sheet having its width disposed lengthwise of such path, such sheet continuously engaging the yarn-carrying portions of the bobbins as the later move across such sheet.

7. In a bobbin stripper, in combination, means for guiding the bobbins along a path, a chamber having a slot which latter extends along the said path, and means propelling air through such slot to impinge initially on the yarn-carrying portions of the bobbins to loosen the ends of the yarn as the bobbins move along such path.

8. In a bobbin stripper, in combination, means for guiding the bobbins along a path, a chamber alongside such path having a slot extending along such path, and a blower forcing air into such

chamber and out through the slot to blow against the bobbins with substantially constant intensity throughout a lengthy extent of movement of each bobbin along such path.

9. In a bobbin stripper, in combination, spaced tracks supporting the bobbins in pendant relation with their tips downward, at least one movable band element engaging the heads of bobbins thus supported to propel them sidewise along the tracks, a chamber alongside the tracks having a slot extending along the tracks so as to confront a plurality of pendant bobbins at one time, means propelling air through such slot to loosen the ends of yarn borne by the bobbins, and a rotary unwinding device to engage and draw off from the bobbins the ends of yarn thus loosened.
